UNITED STATES PATENT OFFICE.

CARL JACOB EMIL FLECK, OF HAMBURG, GERMANY.

SIGNAL-BELL.

SPECIFICATION forming part of Letters Patent No. 656,768, dated August 28, 1900.

Application filed February 8, 1900. Serial No. 4,551. (No model.)

To all whom it may concern:

Be it known that I, CARL JACOB EMIL FLECK, a subject of the German Emperor, and a resident of Hamburg, in the German Empire, have 5 invented certain new and useful Improvements in Signal-Bells, of which the following is a specification.

This invention relates to improvements in signal-bells, and more particularly to that 10 class which is designed for use on street-railway, tramway, and like vehicles; and the object of the improvements is to provide means whereby such signal-bells or signal devices are made more reliable and more effective in 15 use; and with this end in view the invention consists of a signal device comprising two independent bells and a suitable clapper-and-plunger mechanism adapted to sound the said bells simultaneously, so that if one becomes 20 damaged or broken the other still remains effective.

In the accompanying drawings, Figure 1 is 25 a side elevation, partly in section, of the improved signal-bell, the clapper-and-plunger mechanism being in the position of rest; and Fig. 2 is a similar view showing the parts in their working position for sounding the bells.

Similar letters refer to similar parts throughout the views.

30 The two bells *a* and *b*, independent of each other, are freely suspended from a common screw-bolt *m*, supported by a suitable frame or base-plate *i*. The clappers or hammers *c* and *d* (one for each bell) are carried by bent levers *c'* and *d'*, fulcrumed side by side at *c²* and *d²*, respectively, in a slotted bracket *e*, extending from a standard *k* of the base-plate *i*. The clapper-levers are so arranged that their weighted ball-shaped ends or heads *c* 35 and *d*, respectively, will tend to keep the opposite or outer ends, which project through the slotted bracket *e*, together, Fig. 1.

Pivoted to the standard *k* at *f'* is a double-armed lever *f*, one arm of which is formed 40 with a wedge-shaped beak *f²*, adapted to be thrown or moved by a blow or shock between the said outer or free ends of the bent levers in order to part the latter and to operate there-

by the clappers. For imparting to the beak *f²* such a blow or shock a plunger *g*, sliding 50 in a socket *g'*, is arranged above the other or free end *f³* of the lever *f*. By a blow upon the head *h* of the plunger *g* the latter slides down and oscillates the double-armed lever *f*. The wedge-shaped end or beak *f²* of the latter will thereby be forced between the adjacent arms of the bent levers *c'* and *d'* and the clappers *c* and *d* thus be caused to strike and sound both bells *a* and *b* simultaneously, in the construction shown the large bell *a*, for 60 instance, being struck on the outer side by the clapper *d*, while the small bell *b* is struck on the inner side by the other clapper *c*, as will be clearly understood from Fig. 2. The blow, and thereby the sounding of the bells, 65 may be repeated as the plunger is again raised by the back swinging or back oscillation of the lever *f*, which is effected by the action of the weighted clapper-levers upon the wedge-shaped beak *f²*.

In some cases it may be advantageous to effect a more positive return of the clapper-levers into their position of rest, which may be accomplished by means of suitable springs. Instead of employing a double-armed lever *f*, 75 as above described, I may so arrange the bells and clapper-levers that the plunger may be caused to act directly upon the said clapper-levers. For this purpose the said plunger may be provided with a wedge-shaped end or 80 beak and with a suitable spring for returning the same to its inoperative position. As these modifications are self-evident, they need no further description and illustration.

Having fully described my invention, what 85 I claim, and desire to secure by Letters Patent, is—

A signal or call bell comprising two concentrically-arranged bells, bell-crank hammer or clapper levers *c'* *d'*, the actuating-lever *f* and the push-rod *h*, said parts arranged for operation substantially as described.

CARL JACOB EMIL FLECK.
